F. W. Uzann,

Curtain Fixture.

N° 12,524.

Patented Mar 13, 1855

UNITED STATES PATENT OFFICE.

FREDERICK W. URANN, OF SAXONVILLE, MASSACHUSETTS.

CURTAIN-ROLLER.

Specification of Letters Patent No. 12,524, dated March 13, 1855.

To all whom it may concern:

Be it known that I, FREDERICK W. URANN, of Saxonville, in the county of Middlesex and State of Massachusetts, have invented 5 a new and useful Improvement in Curtain or Window Shade Fixtures; and I do hereby declare that the same is fully described and represented in the following specification and the accompanying drawings, letters, figures, and references thereof.

Of the said drawings, Figure 1, denotes a front view of a curtain or window shade having my improvement. Fig. 2, is a vertical and longitudinal section of the curtain 10 roller and the brackets which sustain it.

The nature of my invention consists in providing one of the brackets with a circular chamber or recess for the reception of one of the heads of the pulley of the curtain 15 roller and so that such head may be inserted in the rim and have its outer surface so buried within the recess that the cord wound on the pulley can by no possible means get between the pulley and the bracket.

In the drawings, A denotes the curtain roller, and B and C, the brackets by which it is sustained.

In the bracket, B, a cylindrical socket, *a*, is made for the reception of one end of the 20 roller and to allow such end to freely revolve within such socket. The opposite end of the roller is provided with the sheave pulley or grooved roller, E, which is made in the usual way with two heads, *c*, *d*, and that end of the roller to which it is attached 25 carries a yielding journal, *e*, that rests against and is pressed outward by a spring, *f*, imbedded in the curtain roller.

The bracket, C, is made with a cylindrical 30 chamber or recess, *g*, for the reception of the head, *d*, of the pulley B, and of a depth somewhat greater than the width of the said head, *d*. This recess or chamber has a socket

or bearing, *h*, made axially from it and in 45 the bracket, such bearing being for holding and receiving the yielding journal, which, when placed in it is borne against its end so as to crowd and keep the other journal in its socket.

In order to remove the curtain roller from the brackets it will only be necessary to press it toward the bracket, C, so as to force the yielding journal back into its socket in the 50 roller and far enough to move the other journal out of its socket. This done, by drawing the roller outward, it may be removed from its brackets.

By inserting the head of the pulley within a recess or chamber in the bracket, there is 55 no chance for the cord of the pulley to get caught or pass between the bracket and the head of the pulley, the pulley head serving to keep the cord from chafing against the bracket. By means of my improvement, I 60 am enabled to make the curtain of greater width than it can be when the pulley head is not inserted in the bracket.

I do not claim the inserting of the end or journal of the curtain roller in a chamber 65 or bearing in the socket that supports it, but

What I do claim is—

The improvement of extending the pulley head into the bracket substantially in 70 manner as described and for the purpose of protecting the cord of the pulley from getting between the said head and the bracket during the process of rolling up or unrolling the curtain.

In testimony whereof, I have hereunto set my signature this eleventh day of April 75 A. D. 1854.

FRED. W. URANN.
